EXCAVATIONS IN TUNIS

APPLICATION NO. 100-1111-1111111111

3 REENTS-SHEET 1

No. 892,539.

PATENTED JULY 7, 1903.

W. N. MORRILL,
EXCAVATING MACHINE,
APPLICATION FILED APR. 11, 1908

2 SHEETS--SHEET 2.

UNITED STATES PATENT OFFICE.

WILBUR NATHANIEL MORRILL, OF LOUISVILLE, KENTUCKY.

EXCAVATING-MACHINE.

No. 892,538.

Specification of Letters Patent.

Patented July 7, 1908.

Application filed April 11, 1908. Serial No. 426,427.

To all whom it may concern:

Be it known that I, WILBUR NATHANIEL MORRILL, a citizen of the United States, residing at Louisville, Jefferson county, Kentucky, have invented certain new and useful Improvements in Excavating-Machines, of which the following is a specification.

This invention belongs to that class of excavating apparatus intended mainly for use in sewer construction or pipe-laying work, and designed to excavate the dirt in advance of the sewer or pipe work and to back-fill the excavated material over the completed work.

My present invention aims to improve machines of this class by rendering them more efficient and elastic in their operations, that is to say, better adapted for doing their work economically and under the varying conditions apt to be met with in practical operations.

My invention will be readily understood from the following description taken in connection with the accompanying drawings in which:

Figure 1 is a side elevation of an excavating machine exemplifying my invention, the trench appearing in vertical longitudinal section: Fig. 2 a plan of the machine: Fig. 3 a rear elevation of the excavator proper, the trench appearing in vertical transverse section: Fig. 4 a vertical transverse section of the conveying car and its track: and Fig. 5 an enlarged reproduction of the central portion of Fig. 4.

In the drawings:—1, indicates a pair of rails forming a longitudinal track straddling the location of the trench: 2, the material to be excavated at the heading of the trench: 3, the completed portion of the trench, shown as being protected in the usual manner by sheet piling: 4, completed sewer work in the trench: 5, back-filling over completed portions of the sewer work: 6, a locomotive excavating car mounted to run on the track rails: 7, a jib turntable crane mounted to turn on the excavating car: 8, motive power machinery carried by the crane for operating it and its car: 9, a clamshell excavator suspended from the jib of the crane: 10, a long conveyer car, of skeleton construction, mounted to travel on the track to the rear of the excavating car: 11, a longitudinal series of horizontal rollers supported by the framework of the conveyer car with their axes parallel with each other and transverse to the line of the track: 12, two longitudinal series

of rollers carried by the frame-work of the conveyer car above the level of the rollers 11, the rolls 12 being arranged in pairs, the axes of the two rolls of a pair declining inwardly: 13, an endless conveyer belt engaging rolls at each end of the conveyer car, the lower leaf of this belt running upon the rollers 11, and its upper leaf running upon the rollers 12 whereby the upper leaf of the belt is given a concave or gutter-like form: 14, the rear end of the conveyer car and belt, this end projecting, as a cantaliver, rearwardly beyond the rear wheels of the car: 15, a pulverizer mounted on the front end of the conveyer car and arranged to discharge upon the front end of the conveyer belt: 16, motive power machinery mounted on the front end of the conveyer car for operating the pulverizer and conveyer belt: and 17, couplings, illustrated as chains, connecting the excavating car with the conveyer car and leaving a short open space between the two cars.

Assume the work to be in progress and the sewer builders to be constructing the sewer work as rapidly as the excavation of the trench will permit. The material at the heading of the trench will be excavated by the clamshell and hoisted and delivered into the hopper of the pulverizer which, in turn, delivers the material to the gutter-shaped upper leaf of the conveyer belt, which belt conveys the material rearwardly and back-fills it into the trench over the completed sewer work. The work of the apparatus would thus proceed regularly if everything were working normally and the excavating and sewer building and back-filling could advance uniformly. But if conditions arise in which the sewer building, and consequently the back-filling, must be delayed, the excavating must be proceeded with, the excavated material in such case being deposited at the sides of the trench. Under these conditions the conveyer car will be idle and may, if desired, be uncoupled from the excavating car. When the sewer-building has been resumed or has caught up, then the excavated material deposited at the sides of the trench may be picked up by the clamshell and delivered to the pulverizer to be conveyed back by the belt and delivered into the trench over the completed work.

In Fig. 1 the apparatus is illustrated as excavating between the excavating car and the conveying car, but the clamshell may work ahead of the excavating car, its loads being

then swung around and delivered to the pulverizer. When conditions arise not permitting all excavated material to be back-filled then the clamshell may deliver its loads to 5 wagons alongside the trench. The clamshell may alternate in its working in advance of and behind the excavating car so as to provide facility for the proper and gradual placing of the sheet piling. For instance, the 10 excavator may dig for some distance, working either to the front or to the rear of its car, carrying the work to such depth as first calls for the placing of the sheet piling, the excavator then returning to perform the deeper 15 work where the sheet piling has been already placed, and later returning to the more advanced part of the trench.

I claim:—

1. Excavating apparatus comprising, track 20 rails at the sides of the proposed trench, a locomotive excavating car mounted on said rails, a turntable jib crane mounted for rotation on said car, a clamshell excavator suspended from said crane, and motive power 25 machinery mounted on said car for actuating the car and crane, combined substantially as set forth.

2. Excavating apparatus comprising, track 30 rails at the sides of the proposed trench, a locomotive excavating car mounted on said rails, a turntable jib crane mounted for rotation on said car, a clamshell excavator suspended from said crane, motive power 35 machinery mounted on said car for actuating the car and crane, a long skeleton conveyer car mounted on said rails to the rear of said excavating car, longitudinal series of upper and lower rollers supported by the conveyer car, an endless conveyer belt supported by said 40 rollers, a pulverizer carried by the forward end of the conveyer car and adapted to discharge upon the forward end of said belt, motive power machinery mounted on said 45 conveyer car for actuating said belt and pulverizer, and detachable connections between said locomotive car and conveyer car, combined substantially as set forth.

3. Excavating apparatus comprising, track

rails at the sides of the proposed trench, a locomotive excavator mounted on said rails, 50 a long conveyer car mounted on said rails to the rear of the excavator and coupled thereto, a projection from said conveyer car to the rear of the rear wheels thereof, and an endless conveyer-belt extending the length 55 of the conveyer car and adapted to receive material from the excavator and deliver it rearward of the rear wheels of the conveyer car, combined substantially as set forth.

4. Excavating apparatus comprising, track 60 rails at the sides of the proposed trench, a long conveyer car mounted on said rails, a longitudinal series of transverse rollers carried by said car, two longitudinal series of inwardly declining rollers carried by said cars 65 above the first-mentioned rollers, an endless conveyer belt having its lower leaf supported by the first-mentioned rollers and having its upper leaf supported in gutter form by the upper rollers, an excavator in front of said 70 car, and motive power machinery for actuating the excavator and belt, combined substantially as set forth.

5. Excavating apparatus comprising, track 75 rails at the sides of the proposed trench, a long conveyer car mounted on said rails, a longitudinal series of transverse rollers carried by said car, two longitudinal series of inwardly declining rollers carried by said cars above the first-mentioned rollers, an endless 80 conveyer belt having its lower leaf supported by the first-mentioned rollers and having its upper leaf supported in gutter form by the upper rollers, an excavator in front of said car, a pulverizer carried by the front end of 85 the car and adapted to receive material from the excavator and discharge it upon the front end of the upper leaf of said belt, and motive power mechanism for actuating the excavator and pulverizer and belt, combined substantially as set forth.

WILBUR NATHANIEL MORRILL.
